CONTROL SYSTEM

Edgar H. Bristol, Foxboro, Mass., assignor to The Foxboro Company, Foxboro, Mass., a corporation of Massachusetts

Original No. 1,917,092, dated July 4, 1933, Serial No. 510,926, January 24, 1931. Application for reissue June 29, 1935, Serial No. 29,105

7 Claims. (Cl. 137—139)

This invention relates to control systems which embody a valve or similar mechanism operated by a servo-motor, and the object is to provide improvements in such a system whereby more uniform results may be attained and the effect of mechanical factors, which in previous constructions have adversely influenced the accurate functioning of the mechanism, may be obviated.

My invention may be well understood by reference to the following description of an illustrative embodiment thereof taken in connection with the accompanying drawing, wherein I have shown diagrammatically and partly in section a system of the type wherein a valve is operated by a pneumatic motor thermostatically controlled.

Referring to the drawing, I have there shown a valve 3 adapted to control the flow of some fluid, such as steam, through the pipe 5, the valve being operated by a diaphragm motor 7. The valve herein shown is of the type which is opened by pressure in the motor and closed by the spring 8 when the pressure is relieved. It is adapted to float in partly open positions between open and closed positions. Friction on the valve stem 25 resists movement of the valve and in prior constructions in which the pressure admitted to the motor was proportional to temperature or some other controlling variable, the valve might take different positions accordingly as whether the pressure was increasing to a certain value or decreasing. In accordance with my invention I provide a construction wherein substantially identical positions of the valve may be obtained when desired regardless of the pressure needed to move the valve.

The system shown in the drawing may be supposed to be utilized to maintain a constant temperature in the interior of tank 11 as measured by a suitable thermometric device including the bulb 13 in the tank communicating with a suitable responsive device, as, for instance, the helical Bourdon tube 15 like that shown in the patent to Bristol 1,195,334, dated August 22, 1916. The responsive device 15 may operate one element of a control couple such as the valve or "flapper" 17 which cooperates with a companion element and takes the form of a ported member or "nozzle" 19 which, through the diaphragms 21 and the hollow stem 23 of a double valve 25, provides a communication to atmosphere for the interior of a control head 27 of the supply and waste type. This mechanism is in principle like that described in the patent to Johnson 542,733, dated July 16, 1896, and in detailed construction may be and preferably is similar to that shown in the patent

to Dixon 1,582,868, dated April 27, 1926, while the "flapper" is preferably of the throttling type disclosed in my Patent 1,641,744, dated Sept. 6, 1927.

The valve 25 in the position shown controls the flow of pressure fluid from a supply line 29 through branch 31 to pipe 33. Hitherto it has been customary to permit the air to flow directly to the servo-motor operating the valve. Herein on the contrary pipe 33 leads to a motor 35, herein shown as a helical Bourdon tube or pressure gage adapted to be distorted more or less as the internal pressure varies and carrying on its free end an element of a control couple in the form of a valve or "flapper" 37. The cooperating element consisting of a ported member or "nozzle" 39 is caused to move proportionately to the movements of the valve 3 and herein is shown as mounted directly thereon to reciprocate therewith. The ported member may be in communication through the flexible coil 41, which serves to permit it to move freely, through diaphragms 43 and the hollow stem 45 of a double valve 47 with the interior of control head 49 of the supply and waste type which is interposed between the supply line 29 for air under pressure and conduit 51 leading to the motor 7.

The parts being in the position shown, flapper 17 is raised from its seat on nozzle 19 and air entering the control head at pipe 31 bleeds through the hollow stem 33 and exhausts to atmosphere through the nozzle. Diaphragms 21 are collapsed, valve 25 is in the position shown and air flows through pipe 33 to the motor tube 35, which, being distended, moves flapper 37 downwardly causing it to tend to move away from the ported member 39. Similarly air entering control head 49 from the main line bleeds through hollow stem 45, diaphragms 43 and pipe 41 to atmosphere through nozzle 39. The valve 47 is maintained in the position shown and air passes to the valve motor tending to move the valve toward open position and the nozzle to a position adjacent flapper 37.

Now, as the temperature in tank 11 increases the responsive element 15 is operated and permits valve or flapper 17 to start to close over the port 19 causing pressure to build up in diaphragms 21 thereby causing the valve 25 to start shifting to the right, decreasing communication between 33 and 31 and permitting motor 35 to exhaust to the atmosphere through pipe 33 and the port opened at the left of the valve 25. Flapper 37 therefore moves toward ported member or nozzle 39, building up pressure in diaphragms 43 and causing valve 47 to shift toward the left

reducing the supply of pressure fluid to diaphragm motor 7 and permitting the latter to exhaust to the atmosphere through pipe 51 and the port opened by valve 47 at its right. This begins releasing valve 3 to the action of the spring 9 which commences closing the valve. As the valve moving upward in its closing movement starts to move nozzle 39 away from valve or flapper 31 the couple changes the position 10 of the valve 47 which tends to hold the nozzle 39 and valve 3 in the position corresponding to the position assumed by flapper 31.

It will thus be seen that the thermometric device 15 and control head 27 with its control 15 couple 17 and 18 establish a certain pressure in motor tube 35 corresponding to a given temperature and that to any pressure in motor tube 35 there will correspond a position of nozzle 39 and with it of the valve and its stem, this position being brought about by a pressure applied through control head 49 to diaphragm motor 7, which pressure in the motor 7 may or may not be identical with the pressure in 35.

A gradual change in pressure in motor 35 is 25 attained when flapper 17 is of the throttling type described in my Patent 1,641,744 above referred to. Alternatively or in conjunction therewith I may utilize a restriction 53 in pipe 33 which permits only a slow seepage of air therethrough.

30 I prefer to provide for a gradual flow of energy to and from the valve operating motor 1 in response to a governing action of the mechanism, and herein I have shown pipe 51 as provided with the restriction 53 for damping the flow of 35 air therethrough. In the absence of such restriction the motor may tend to pulsate because of the fact that the resistance to initial movement of the valve is greater than the sliding friction of the valve stem once the motion has begun. In many cases pulsation is undesirable. Furthermore, in cases where the control couple separates completely it is possible that a sudden impulse of air under full pressure may be applied, tending to open the valve, and before this 40 can be released, the valve may have moved beyond its desired position. The use of a restriction 53 corrects this.

While I have for purposes of clearness and by 50 way of illustration described a pneumatically operated valve thermostatically controlled, I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

60 I claim:

1. In combination with a valve having a pressure-fluid-operated motor for operating the same, means controlling the supply of pressure fluid to the motor comprising a valve mechanism 65 of the supply and waste type, a control couple therefor, the relative approach and recession of the elements of which govern the said valve mechanism, one element of which couple is moved proportionately to movement of said valve, the relative position of said elements being further controlled by a pressure-fluid-operated device, means controlling flow of fluid to said device comprising a valve mechanism of the supply and waste type and a control couple, 70 and means responsive to the fluctuations of a

variable condition for relatively positioning the elements thereof.

2. In combination with a motor-operated valve comprising a control couple, the relative approach and recession of the elements of which govern the supply of energy to the motor, one element of the couple moving proportionately to the valve, a tube subject to distorting internal pressure connected to one of said elements for further controlling the relative positions of the same, and means to admit pressure fluid to said tube comprising a fluid pressure control mechanism of the supply and waste valve type including a control couple, one element of which affords a port to atmosphere and the other a valve 15 for said port, the relative approach and recession of said elements governing the pressure in the system, and means responsive to the fluctuations of a variable for relatively positioning the elements of said second couple. 20

3. In combination with a motor-operated valve comprising a control couple, the relative approach and recession of the elements of which govern the supply of energy to the motor, one element of the couple moving proportionately to the valves, a 25 pressure-fluid-operated motor for moving the other element, and means controlling the flow of fluid thereto comprising a valve mechanism of the supply and waste type, a control couple therefor, the relative approach and recession of the elements of which govern the said mechanism, and means responsive to the fluctuations of a variable condition for relatively positioning the elements thereof. 30

4. In combination with a valve having a pressure-fluid-operated motor for operating the same, a conduit for the fluid having a restriction for dampening the flow to and from the motor means, means controlling the flow of fluid through the conduit comprising a valve mechanism of the supply and waste type, a control couple therefor, the relative approach and recession of the elements of which govern the said valve mechanism, one element of which couple is moved proportionately to movement of said valve, the relative position of 45 said elements being further controlled by a motor, a second control couple, the relative approach and recession of the elements of which govern the supply of energy to said latter motor, and means responsive to the fluctuations of a variable condition for relatively positioning the elements of 50 said second couple.

5. Apparatus for positioning a movable member in accordance with the position of a condition responsive member comprising, in combination, a motor for moving the movable member, a source of fluid under pressure capable of furnishing said motor with the power necessary to move the movable member to and to maintain it at desired positions under varying adverse conditions of friction and the like, a throttling control valve for controlling the supply of fluid pressure to the motor in accordance with the operative position of said control valve, means including a pneumatic control couple for positioning said control valve in accordance with the operative value of said couple, said valve being determined by the position of said condition responsive member and the position of said movable member, and said couple having a relatively small throttling range as compared with the throttling range of said control valve whereby the power is supplied to said motor necessary to move the valve to and maintain it in positions in accordance with the position of said condition responsive member. 55 60 65 70 75 80 85 90 95

6. In mechanism for controlling the flow of energy governing a motor which exerts a force on a movable member proportional at all times to said flow of energy, apparatus for operating said motor to position said movable member in proportional correspondence with a predetermined force value comprising first control means frictionlessly changeable in position in proportional correspondence with change in the value of said predetermined force, second control means 10 changeable in position in proportional correspondence with the position of said movable member, a control couple for controlling the flow of energy, said first and second control means so governing said control couple that the force exerted by said motor on said movable member is proportional to the relative positions of said first and second control means over a narrow range of relative positions and is maximum for relative positions outside one end of said narrow range and minimum for relative positions outside the other end of said narrow range whereby said second control means and said movable member are caused to assume positions in substantial corre-

spondence with change in said predetermined force value.

7. In apparatus for controlling the supply of air to a pneumatic motor operating against spring means to position a movable member, mechanism 5 for causing said motor to position said movable member in proportional correspondence with a predetermined force value comprising first control means including a low pressure pneumatic couple, one element of which provides a port to 10 the atmosphere and the other element of which affords a valve for said port, the relative positions of said elements governing the supply of air to said motor, second control means frictionlessly positionable in proportional correspondence with 15 the value of said predetermined force, third control means positionable in proportional correspondence with the position of said movable member, said second and third means relatively positioning said elements, whereby movement of 20 said second control means by said predetermined force causes said third control means to follow within the limit of the throttling range of said control couple.
